UNITED STATES PATENT OFFICE.

GEORGE L. SOLTER, OF PHILADELPHIA, PENNSYLVANIA.

BOXED DEMIJOHN.

SPECIFICATION forming part of Letters Patent No. 325,875, dated September 8, 1885.

Application filed May 21, 1885. (No model.)

To all whom it may concern:

Be it known that I, GEORGE L. SOLTER, a citizen of the United States, and a resident of the city and county of Philadelphia, and State of Pennsylvania, have invented a new and useful Improvement in Boxed Demijohns, of which the following is a specification.

My invention relates to an improvement in that class of boxed demijohns in which the neck of the bottle projects above the top of the box or case which incloses the bottle; and the object of my invention is to furnish, in connection with the box or case and suitable means for packing the bottle, a cover for the neck of the bottle which will be simple and inexpensive, and which will effectually prevent the neck of the bottle from being injured during transportation.

Heretofore incased bottles have been provided with flat tops resting on the body-case, as in United States Patent No. 170,246, and with a wire guard similarly placed to indicate the contents of the bottle, as in United States Patent No. 215,852. The necks also of bottles projecting from the body-case have been covered by a cap resting on the neck alone.

My invention differs from these in this, that it consists of a conical cover of sheet metal or equivalent material designed to cover and rest on the whole body-case, and thus to afford a broad base, also by its conical form to cover the projecting neck of the bottle with least material and to resist pressure most effectually, and, further, by its pointed top to prevent the placing of heavy weights thereupon. It also affords a closely-covered space between the neck of the bottle and the periphery of the box for the accommodation, if desired, of measures, funnels, or other articles used in dispensing liquids, and confines the odors and diminishes the evaporation of such liquids as may have reached the exterior of the box.

In the accompanying drawings, forming part of this specification, and in which similar letters of reference indicate similar parts throughout the several views, Figure 1 is a central sectional elevation of my invention, the cover being thrown back; Fig. 2, a side view, the top being closed; Fig. 3, a top view of the case; Fig. 4, a sectional elevation of the washer upon which the bottom of the bottle rests, and Fig. 5 a plan of the same.

A is the bottle; B, a cylindrical box or case in which the body of the bottle is inclosed; C, a space between the box and bottle, which is filled with some soft material, hay being preferable; D, an opening in the top M of the box, through which the neck of the bottle passes; E, a packing of rubber or similar material, which is secured to the top of box B, and which clasps the neck of the bottle tightly.

F is a conical lid, constructed of one piece of tin or sheet-iron, the base of which is of the same or of a slightly smaller diameter than the cylindrical box B, and which when closed bears upon the top of B. This conical top is hinged to B at G, and is furnished with a hasp, H, by means of which it may be locked to B.

I is a rubber washer fastened to the bottom of box B and furnished with a central opening, J.

K is an opening in the bottom of B, corresponding with the opening J in I.

L are handles, by means of which the demijohn may be lifted.

The neck of the bottle projects a sufficient distance above the top M of the box B to allow its contents to be emptied without danger of any being lost. The neck is kept from coming in contact with the top of the box by the packing E, which is yielding, and prevents the neck from being thrown suddenly against the top and broken by rough handling. The washer I, against which the bottom of the bottle rests, is hemispherical in shape and fits in the depression in the bottom of the bottle, and keeps the bottle in place and prevents it from coming in contact with the bottom of the case B.

By means of the openings J in I and K in B the bottle may be inspected to ascertain if it is clean.

By means of the hasp H the lid may be locked to the box to prevent the contents of the bottle from being tampered with.

All sidewise movement of the bottle is prevented by the packing in C.

The conical lid F incloses without touching the neck of the bottle, its base bearing on the top of the box B, and any blows given to this lid are transmitted directly to the box B instead of to the bottle. This lid is hinged to the box B, and when it is desired to pour off the contents of the bottle it is only necessary to throw back the lid, not to remove it, in or-

der to have the neck of the bottle entirely exposed.

I claim—

In combination with the cylindrical case B
5 and the body of the bottle inclosed therein,
with its neck projecting through the top of
the box, a cover of sheet metal conical in form,
having its base of substantially the dimensions

of the case-top and resting thereon, and with
its pointed top covering the neck of the bot-
tle, all as set forth.

GEO. L. SOLTER.
